UNITED STATES PATENT OFFICE.

JOHN ARTHUR KAYE, OF SAULT STE. MARIE, ONTARIO, CANADA.

SWIMMING DEVICE.

1,329,660.

Specification of Letters Patent.

Patented Feb. 3, 1920.

Application filed November 13, 1919. Serial No. 337,889.

To all whom it may concern:

Be it known that I, JOHN ARTHUR KAYE, a subject of the King of Great Britain, residing at Sault Ste. Marie, Province of Ontario, in the Dominion of Canada, have invented a new and useful Swimming Device; and I do hereby declare the following to be a full, clear, and exact description of the invention, such as will enable others skilled

10 in the art to which it appertains to make and use the same.

The present invention relates to an improved swimming appliance, and has for its object to provide a device of this character 15 which embodies novel features of construction whereby it will assist in causing the arms and legs to be moved in the proper manner and relation to each other when learning to swim.

20 Further objects of the invention are to provide a device of this character which is comparatively simple and inexpensive in its construction, which can be readily placed in position and will serve as a life preserver as 25 well as a swimming appliance, and which provides an effective connection between the arms and legs of the swimmer, whereby the said members are assisted in moving in the proper relation to each other for swimming.

30 With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

40 Figure 1 is a front elevation of a swimming appliance constructed in accordance with the invention, showing the same as applied to a swimmer, one position being shown by full lines and another position being shown by dotted lines.

Fig. 2 a detail view of one of the pawl and socket joints.

Fig. 3 is a detail sectional view through one of the leg bands.

50 Fig. 4 is an enlarged detail view of the pivotally mounted sleeves which carry the swinging arms.

Fig. 5 is a detail view of one of the wrist bands, and

55 Fig. 6 is a plan view of the belt.

Corresponding and like parts are referred

to in the following description and indicated in all the views of the drawings by the same reference characters.

Referring to the drawings, which illustrate one possible embodiment of the invention, the numeral 1 designates a life belt which is adapted to be fitted around the waist of the swimmer, said life belt being formed of some buoyant material such as 60 cork, and being provided at the back thereof with suitable straps 2 by means of which it can be secured in position. The swimmer or person to which the device is applied is indicated at S, and the front of the belt 1 70 may be provided with a buoyant breast piece which extends upwardly over the breast of the swimmer, thereby tending to float the swimmer in the water and hold him in proper position. Suitable straps 4 are provided for holding the breast piece in position.

A pivot bolt 5 projects from the front of the belt 1 and extends transversely through a pair of sleeves 6 which are loose thereon. 80 Arms or rods 7 are threaded in the ends of the sleeve 6 or otherwise rigidly connected thereto and extend in opposite directions from the respective sleeves. These arms and sleeves coöperate with each other to provide 85 a pair of intersecting levers which are pivotally mounted upon the bolt 5. These levers are connected at points adjacent the pivot bolt 5 by the four tension springs 8 which are arranged in parallel pairs, said springs 90 merely serving to offer a slight yielding resistance to a swinging movement of the levers in either direction.

The extremities of the arms 7 terminate in sockets 9 which loosely receive balls 10 at 95 the ends of links 11. One pair of these links 11 loosely engage bands 12 which may be applied to the arms or wrists of the swimmer at any desired position. The other set of links 11 loosely engage leg bands 13 which 100 may be applied to the legs or ankles of the swimmer in any desired position. These links 11 are shown as passing slidably through guide eyes 14 on the arm bands and leg bands, and as provided with spaced stops 105 15 which are adapted to engage the guide eyes after a limited sliding movement of the links through the same in either direction. The arms and legs of the swimmer are thus enabled to have a limited amount of movement independently of the links and levers, 110 and the discomfort and annoyance which

would be incident to a more positive connection of the members is thus avoided. This sliding connection also allows for the peculiar individual movements of the arms and legs which are necessary to swim effectively and which are not such as follow any set mechanical rules.

In order to cause the levers to move in synchronism, that is, to swing corresponding amounts in opposite directions, the breast piece 3 is shown as provided with a slideway 16. A slide 17 is mounted therein and pivotally connected by the rods 18 to the upper set of arms 7. With this arrangement both of the levers always move corresponding amounts in opposite directions. This appliance serves to couple the arms and legs of a swimming student together in such a manner that the arms must move in unison and a movement of the arms in one direction must be accompanied by a corresponding movement of the legs. Many persons have great difficulty in moving the arms and legs at the same time when learning to swim, and the use of an appliance of this character will tend to overcome this difficulty. Furthermore, the life belt supports the swimmer in the water while he is mastering the arm and leg movements, so that the art of swimming is simplified and made as easy as possible for the swimmer.

Having thus described the invention, what I claim as new and desire to secure by Letters Patent, is:—

1. A swimming appliance including a belt, a pair of crossed levers pivotally mounted upon the belt, arm bands, leg bands, and links loosely connecting the arm bands and leg bands to the corresponding ends of the respective levers.

2. A swimming appliance including a belt,

a pair of crossed levers pivotally mounted on the belt, arm bands, leg bands, and links having limited sliding connections with the leg bands and arm bands and loosely connected to the corresponding ends of the respective levers.

45

3. A swimming appliance including a belt, a pair of crossed levers pivotally mounted on the belt, arm bands, leg bands, links loosely connecting the arm bands and leg bands to the corresponding ends of the respective levers, and an operative connection between the levers for causing them to move in synchronism.

50

4. A swimming appliance including a belt, a pair of crossed levers pivotally mounted on the belt, arm bands, leg bands, links loosely connecting the arm bands and leg bands to the corresponding ends of the respective levers, a breastpiece provided with a slideway, a slide in the slideway, and rods pivotally connecting the slide to the levers for causing the same to swing in synchronism.

60

5. A swimming appliance including a belt, a pair of crossed levers pivotally mounted on the belt, arm bands, leg bands, links having limited sliding connections with the arm bands and leg bands and loosely connected to the corresponding ends of the respective levers, a slide, and guide means for the slide, and rods pivotally connecting the slide to the levers for causing them to swing corresponding amounts in opposite directions.

65

In testimony whereof I have signed my name to this specification in the presence of two subscribing witnesses.

JOHN ARTHUR KAYE.
